UNITED STATES PATENT OFFICE.

JOHN McARTHUR, OF BROOKLINE, MASSACHUSETTS.

SASH-OPERATING MECHANISM.

Application filed October 14, 1924. Serial No. 743,613.

The purpose of the invention is to provide an effective device for the purpose of raising and lowering windows, particularly such as are used on closed vehicles, the device being susceptible of production in a cheap form so that it may be readily manufactured and, therefore, installed at small cost.

With this purpose in view, the invention 10 consists in a construction and combination of parts of which a preferred embodiment is illustrated in the accompanying drawings, wherein:

Figure 1 is a front elevational view of 15 the invention applied in operative position on a vehicle door for the actuation of the window thereof.

Figure 2 is an enlarged detail sectional view on the line 2—2 of Figure 1.

Figure 3 is an enlarged elevational view 20 of the operating mechanism detached.

Figure 4 is a transverse sectional view on the line 4—4 of Figure 3.

Figure 5 is a transverse sectional view 25 on the line 5—5 of Figure 3.

Figure 6 is a detail elevational view of the connecting means between the operating 30 cord or cable and the window.

Figure 7 is a plan view of the structure 35 shown in Figure 6, the cable being shown in section.

The invention is housed in the sash pocket and comprises an operating cable 1 traversing the upper and lower guide pulleys 2 and 3, the latter being rotatably mounted at the opposite ends of a base member 4, preferably a casting, of cross sectionally channel form to insure it against bending, and provided at the upper end 40 with a lateral offset extension 5 carrying a pin 6 on which the gear 7 is rotatably mounted, the gear on opposite sides carrying the sheaves 8 and 9 consisting preferably of stamping riveted or otherwise secured to 45 the gear. The extremities of the cable 1 are secured one to one of the sheaves and the remainder to the other the sheaves being radially bored, as indicated at 10, and the terminals of the cable extending through 50 said openings 10 for the reception by clamps 11 mounted on the gear within the peripheries of the sheaves. Obviously, the rotation of the gear will effect longitudinal movement of the cable in one direction or 55 the other depending upon the direction of rotation.

The gear 7 is actuated by means of a pinion 12 rotatably mounted on a spindle or pin 14 carried by the base member 4 and by a bracket member 15 spanning the gear 60 and secured to the base member by bolts or screws 16. The spindle or pin 14 terminates in a crank 17 exteriorly exposed, so that rotary movement may be imparted to the pinion and thus to the gear 7 and the sheaves 65 carried thereby.

A yielding latch is provided to retain the pinion in adjusted position and this latch consists of a spring 18 secured to the base member 4 and provided with a nose 19 engaging between the teeth of the pinion. When the crank 17 is turned, the latch member will be deflected to permit rotation of the pinion and the gear, but upon cessation of the turning movement of the crank, the latch member will engage between the teeth of the pinion and prevent rotation of the latter under ordinary strain and thus will preclude rotation of the gear and arrest movement of the cable, with the result that 75 the window with which the cable is operatively connected is held at the desired adjustment.

To retain the proper tension on the operating cable 1, an idle roller 20 is provided 80 and is rotatably mounted at the extremity of an arm 21 carried by the base member and pivotally connected with the latter, pressure of the idle roller upon the cable being effected by means of a compression 85 spring 22 telescoping a pin 23 carried on the arm and a pin 24 of angular form and selectively insertible in any one of a series of eyes 25 formed in the base member. Obviously, by the selection of the desired eye 90 25, the pressure of the spring 22 may be regulated to secure the desired pressure of the idle roller.

The means for connecting the cable with the window consists of an angular plate 26 100 connected with the web of the channel 27 of the window frame, said angular plate being provided with a stud 28 disposed parallel to the flange connected with the channel and bored transversely for the reception of 105 a cotter pin 29 which serves to retain the connector 30 in place on the stud 28, the connector having an eye for pivotal movement with the stud, with a compression spring 31 in surrounding relation with the 110 stud and disposed between the connector and the plate, washers 32 being disposed be-

tween the spring and the connector and between the latter and the cotter pin.

The connector is of angular form, as shown, and is secured to the operating cable 5 by means of a clamp 33, the cable resting in the angle of the angular portion 34 of the connector and the clamp spanning said angle and passing through a slot 35 formed in the angular portion having an angular extremit 10 to effect an interlock between it and the angular portion of the connector. A bolt 37 constitutes the means for securing the other end of the clamp to the connector, the intermediate portion spanning the cable 15 resting in the angle of the angular portion 35 and said intermediate portion being transversely arched to provide lip elements 38 for embedding in the cable and thus effectively securing it in engagement with the connector.

The invention having been described, what is claimed as new and useful is:

1. In combination with a sliding window, a base member having idler rolls at its extremit 20ies, a cable trained over said idler rolls and connected at an intermediate point

with said window, a pair of sheaves mounted for rotation on a common axis and in synchronism, and means for turning said sheaves, the sheaves being each radially bored and the extremities of the cable being connected one to each of the sheaves and extending through the bores and anchored on the sides thereof.

2. In combination with a sliding window, 35 a base member, idler rolls disposed at the extremities of said base member, a cable trained over the idler rolls and operatively connected with the window, a cable actuating means consisting of a gear, sheaves disposed on opposite sides of the gear and axially aligned therewith and connected thereto, the sheaves being formed with radial bores and the extremities of the cable being extended through said bores and anchored to the sheaves, and an actuating pinion in mesh with said gear and provided 40 with a yielding latch member engaging its teeth.

In testimony whereof he affixes his signature.

JOHN McARTHUR.
